CLAIM

I claim the ornamental design for a balance holder, as shown and described.

DESCRIPTION

FIG. 1 is a Perspective view of a balance holder showing my new design;

FIG. 2 is a Front view thereof;

FIG. 3 is a Back view thereof;

FIG. 4 is a Right-side view thereof;

FIG. 5 is a Left-side view thereof;

FIG. 6 is a Top view thereof;

FIG. 7 is a Bottom view thereof; and,

FIG. 8 is a Top view of a balance holder showing in open position.

The broken line depicted on the product is for illustration purpose only and form no part of claimed design.
